(57) **CLAIM**

The ornamental design for a head for bead filtration system, as shown and described.

DESCRIPTION

FIG. 1 is a perspective view of the head for bead filtration system according to this invention;

FIG. 2 is a front elevation view of the invention;

FIG. 3 is a right side view of the invention, the left side view being a mirror image;

FIG. 4 is a rear elevation view of the invention;

FIG. 5 is a bottom plan view of the invention;

FIG. 6 is a top plan view of the invention; and,

FIG. 7 is a perspective view of a second embodiment of the head for bead filtration system of this invention, the only difference being in the appearance of the bottom.
